UNITED STATES PATENT OFFICE.

HENRIK CHRISTIAN FREDRIK STÖRMER, OF CHRISTIANIA, NORWAY.

APPARATUS FOR WASHING AMALGAM.

SPECIFICATION forming part of Letters Patent No. 600,211, dated March 8, 1898.

Application filed June 26, 1895. Serial No. 554,083. (No model.)

To all whom it may concern:

Be it known that I, HENRIK CHRISTIAN FREDRIK STÖRMER, a subject of the King of Sweden and Norway, residing at Christiania, 5 in the Kingdom of Norway, have invented certain new and useful Improvements in Apparatus for Washing Amalgam; and I do hereby declare the following to be a full, clear, and exact description of the invention, such as 10 will enable others skilled in the art to which it appertains to make and use the same, reference being had to the accompanying drawings, and to letters of reference marked thereon, which form a part of this specification.

15 In the electrolytic decomposition of aqueous solutions of the salts of the metals of the alkalies in contact with a mercury cathode detrimental secondary reactions take place, resulting from the reaction of the separated 20 metal upon the water of the electrolyte, whereby the latter is decomposed, giving rise to undesirable secondary products and consequent loss of electric energy. This reaction of the separated metal upon the water of the 25 electrolyte takes place whether the mercury cathode is quiescent or flowing continuously to and from the apparatus. In the former case the reaction of the metal upon the water of the electrolyte is due chiefly to the fact 30 that the mercury becomes saturated with the metal to such a degree as to reduce its power of absorption too much, while when the cathode is flowing continuously it carries along with it a certain quantity of water from the 35 electrolyte, which is immediately decomposed.

From what has been said it will be seen that the main difficulty lies in maintaining the surface of the mercury in contact with the electrolyte in a quiescent state and at the 40 same time preventing too great an accumulation of metal in the surface stratum of the mercury.

I have found by actual practice both with a flowing and a quiescent cathode that it is 45 possible to obtain and maintain in contact with the electrolyte quite a distinctive or separate thin layer or film of amalgam, while the body of mercury below such film can be kept in constant agitation without destroying said 50 layer or film. It is therefore evident that the tendency of the surface layer to decompose the water of the electrolyte decreases in pro-

portion to the increase of the power of absorption of the body of mercury underlying said layer or film and containing a less percentage 55 of metal than said layer or film. If, on the other hand, a permanent thin surface layer or film of mercury containing a high percentage of metal is provided and the body of mercury underlying said layer is agitated or 60 mixed up, the power of absorption of the mercury cathode is more energetic and capable of completely counteracting the tendency to decomposition of the water of the electrolyte, and this is the case whether the mercury 65 cathode is quiescent or flowing continuously. Accordingly the electrolytic decomposition of solutions of the salts of the metals of the alkalies may be effected in presence of or in contact with a quiescent or a continuously- 70 flowing mercury cathode, provided a more or less concentrated practically quiescent thin layer or film of amalgam is maintained in contact with the electrolyte while the body of mercury underlying such layer or film is 75 continuously agitated to prevent the accumulation of metal in said surface layer or film, and consequently the increase in the depth or thickness thereof, by mixing the metal separated and passing through the film 80 with such underlying body of mercury.

In case the mercury cathode is a quiescent one the electrolytic decomposition is of course intermittent, as it becomes necessary to remove the cathode before the amalgam becomes too much concentrated, while the operation is made a continuous one with a flowing cathode.

The construction of apparatus suitable for the carrying out of my invention, particularly the means for stirring the body of mercury without disturbing or breaking up the surface film of practically quiescent amalgam, may be variously modified, as shown in the accompanying drawings, in which— 90

Figure 1 is a vertical longitudinal sectional view of one form or construction of apparatus, and Figs. 2 and 3 are like fragmentary views illustrating structural modifications.

Referring to Fig. 1, which illustrates an 100 electrolytical apparatus in which provision is made for a continuous flow of the mercury cathode through such apparatus, A indicates a vessel of suitable form and material, pref-

erably of a non-conducting material, as earthenware, cement, or the like, provided with a cover B, a feed branch or port J, an overflow or exhaust branch or pipe K, and a branch 5 or pipe L for drawing off the gases evolved at the anode. A pipe E, connected with the vessel A at one end and near its bottom and terminating in a funnel-shaped mouth, serves to supply the apparatus with mercury, a discharge-pipe leading from near the bottom of said vessel at its opposite end into a trap F, closed by a suitable stuffing-box H, in which the bent end of the eduction-pipe G is adjustable for the purpose of adjusting or varying 10 the depth of mercury in vessel A. If the vessel A is constructed of a non-conductive material, I place upon the bottom thereof a conductive plate C, as a plate of cast-iron, which is connected with the negative pole of 15 the source of electricity, the upper surface of the plate being preferably planed or otherwise trued to a substantially plane surface, over which the mercury is caused to flow. From the cover B of vessel A depends a tubular guide-sleeve S for a rod N, whose lower 20 end is guided in a step or socket R in the bottom of the vessel A, the upper end of said rod being connected to an eccentric O on a shaft P, the guide-sleeve S dipping into the 25 stratum of mercury D. To the lower end of rod N, at a suitable distance from the conducting-plate C, is secured a perforated plate M, which may be of iron, ebonite, or other suitable material or substance not injuriously 30 affected by the mercury cathode, and at a suitable distance above the latter is arranged the anode, which is preferably composed of a frame U, in which a series of carbon rods T are secured in the form of a grating, 35 said frame being supported from brackets V on the inner face of the walls of vessel A. It is obvious that when the shaft P is revolved a vertical reciprocating motion is imparted to the plate M, and as this plate 40 is perforated the mercury is forced through the perforations of the plate at each upward and downward movement thereof. In the upward movement of the plate the mercury is caused to flow in a downward direction, 45 carrying along with it the greater part of the amalgam formed, while during the downward movement of the said plate the mercury is caused to flow upwardly through the perforations thereof, thereby effecting an intimate 50 admixture of the separated metal or amalgam formed with the whole of the body of mercury, and if the flow of such mercury through the vessel is properly regulated the outflowing amalgam will contain a much higher percentage 55 of metal than would be the case otherwise. The electrolyte is fed in a continuous regulated stream through feed-port J and flows off through overflow-pipe K, while the mercury in a continuous stream is fed to the apparatus through pipe E and flows out of the apparatus through pipe G, and it is obvious 60 that if the inflow and outflow of the 65

mercury, as well the outflow-level, are suitably regulated there will at all times be a substantially quiescent layer of amalgam in contact with the electrolyte. On the other hand, by suitably regulating the amplitude of reciprocation of the perforated plate M the thickness of the practically quiescent surface layer or film of amalgam can also be determined and the amalgam formed, which would otherwise increase the thickness of the surface layer, is mixed with the body of mercury underlying said surface layer without disturbing the same. 70 75 80

In Fig. 2 I have shown a corrugated or rifled plate, the connections e' and f' between the feed and discharge pipes being of course flexible to admit of the vertical reciprocation of the said rifled plate. In this arrangement 85 the movable plate is constructed in the form of a shallow tray or trough M' , through which the mercury is caused to flow, the entire body of mercury being here alternately lifted and lowered with the tray, thereby alternately varying the speed of flow of the mercury over the riffles or corrugations and imparting to such mercury the desired motion whereby the mixture of the metal or amalgam throughout the body of mercury is effected, 90 the mercury being in this arrangement directly connected with the negative pole of the electrical source. 95

In Fig. 3 I have shown the vessel A provided with a false bottom M^2 , provided with 100 riffles or corrugations or equivalent devices, said false bottom or plate being connected by rod N^2 to any suitable device, as an eccentric, adapted to impart to said plate a reciprocating motion in a horizontal plane, the cathode 105 being a non-flowing—*i. e.*, a quiescent—one, the admixture of the metal or the distribution of the amalgam throughout the body or bulk of mercury being effected by the reciprocating or jiggling motion of the plate. 110

In Fig. 2 I have shown the riffles or corrugations in the form of saw-teeth inclined toward the outflow-port, so as to facilitate the flow of the cathode in that direction, while in Fig. 3 the riffles or corrugations consist of parallel ribs of polygonal form in cross-section. The form of these ribs and the depth of the intermediate depressions may, however, be varied, as indicated at the right-hand end of the plates M' and M^2 , as the conditions of service may require.

It will therefore be seen that the means for carrying my invention into practical operation may be varied in many ways without departing from the spirit thereof, the essential 125 feature of which consists in maintaining a practically quiescent thin stratum or film of amalgam in contact with the electrolyte and imparting to the body of mercury underlying said stratum or film such a motion as to mix 130 therewith the metal separated and passing through the film and which would otherwise accumulate on the surface of the cathode and react upon the electrolyte.

Having thus described my invention, what I claim as new therein, and desire to secure by Letters Patent, is—

1. In an electrolytic apparatus, the combination with a suitable vessel containing a layer of mercury as cathode and a suitable anode, of a mixer consisting of a plate normally immersed in and of substantially the same superficial area as that of the cathode, and means for imparting to said plate a reciprocating motion, for the purpose set forth.
2. In an electrolytic apparatus, the combination with a vessel containing a layer of

mercury as cathode, and a suitable anode, of a mixer consisting of a perforated plate normally immersed in and of substantially the same superficial area as that of the cathode, and means for imparting to said plate a vertical reciprocating motion, for the purpose set forth.

In witness whereof I have hereunto set my hand in presence of two witnesses.

HENRIK CHRISTIAN FREDRIK STÖRMER.
